M. MOIR.

BED.

APPLICATION FILED JAN. 2, 1917.

Patented Aug. 24, 1920.

Inventor
Mabel Moir
By Lincoln Somtag,
Attorney.

UNITED STATES PATENT OFFICE.

MABEL MOIR, OF SAN FRANCISCO, CALIFORNIA.

BED.

1,350,327.

Specification of Letters Patent. Patented Aug. 24, 1920.

Application filed January 2, 1917. Serial No. 140,262.

To all whom it may concern:

Be it known that I, MABEL MOIR, a citizen of Great Britain, residing at the city of San Francisco, in the county of San Francisco and State of California, have invented 5 certain new and useful Improvements in Beds, of which the following is a specification.

My invention relates to improvements in 10 wall-beds.

The object of my invention is to provide a wall-bed in two separable sections, each 15 of said sections comprising a complete bed, but said sections being so joined that they may readily be united to form a double-bed, or separated so as to form so-called "twin-beds."

Wall-beds are used mostly in apartment 20 houses to obtain space for other furniture and to remove the appearance of a bedroom and also to obviate the desirability of careful bed-making for the sake of appearance.

While differing in design or mechanism 25 for the raising, lowering and swinging or handling the same they have heretofore constituted double-beds only as intended for the use of a plurality of persons under the same coverings. Apartments are mostly occupied by two persons, males or females, or 30 husband and wife, and the sleeping of two persons under the same coverings is not conducive to good health or comfort, but on the contrary may be harmful.

To overcome such objections to the use 35 of wall-beds, I have invented "twin" wall-beds to take the place of the present "double" wall-beds, retaining the good features of the latter, with novel connections between the two beds so as to provide an 40 economical, unobjectionable and effective means for the sleeping of two persons under different coverings.

Although I have shown in the accompanying 45 drawing the preferable construction of my invention, I claim all modifications which may fall within its spirit and scope.

In the accompanying drawing illustrating 50 my invention Figure 1 is a perspective view of the same when the beds are separated for use. Fig. 2 is an end view of my wall

beds when the same are united for use as a double-bed.

In the drawing A shows one of the wall-beds embodying my invention movably connected to a wall or stanchion and B shows a view of said beds not connected to the wall. In bed or section A, 1 designates a slideway; and in bed or section B, 2 is a rod slidable in said slideway. The rod 2 is provided at its free end with a knob for preventing the withdrawal of the rod from the slideway. The invention is preferably arranged with two rods and slideways as mentioned, one of said rods and one of said slideways 65 in which the rod works being positioned at each end of the beds, but the rods and slideways may be arranged otherwise without departing from the spirit of my invention. By the arrangement of the beds as shown 70 longitudinal movement of the same from each other is prevented, while transversely the beds may be moved so as to constitute twin-beds or a double-bed as desired.

In Fig. 1 my invention is shown separated for use as a "twin bed" and for different coverings, and in Fig. 2 the same is shown with the sections thereof united so that the same may be used as a double-bed and with the same coverings. The 80 slideways are provided with in-turned flanges so that the rods 2 are prevented from removal from section A.

The head of bed A is hung in a frame by means of straps as shown in Fig. 1 and which frame is hinged to a post or fixed support.

I claim:—

In combination with a fixed support, a frame centrally hinged to said fixed support 90 and sustained thereby, a pair of beds in alinement, the head of one of said beds being hung within said frame and provided with a slideway extending transversely therein and the foot of said bed being provided with a slideway at its base extending transversely therein, the openings of said slideways being narrower than the inner portion thereof, and the other of said beds being provided with a rod extending transversely therefrom at the head of said bed 95 and slidable in the slideway in the front 100

portion of the bed connected to said frame, and the foot of said bed provided with said rod being provided with a rod slideable in the slideway in the rear portion of the bed 5 connected to said frame, and each of said rods being provided with a head in the slideway in which it is slideable of greater diameter than the opening of said slideway.

In testimony whereof I affix my signature in presence of two witnesses.

MABEL MOIR.
